Primary Examiner — Austin Murphy(74) *Attorney, Agent, or Firm* — Paul R. Martin(57) **CLAIM**

The ornamental design for a post puller, as shown and described.

DESCRIPTION

FIG. 1 is a perspective view of my new design for a post puller.

FIG. 2 is an top plan view of my new design for a post puller.

FIG. 3 is an front elevational view thereof.

FIG. 4 is a front end elevational view thereof.

FIG. 5 is a rear end elevational view thereof.

FIG. 6 is a rear elevational view thereof; and,

FIG. 7 is a bottom plan view thereof.

The broken line elements in FIG. 1 are environmental, and form no part of my new design.
